UNITED STATES PATENT OFFICE.

WILLIAM R. FOX, OF GRAND RAPIDS, MICHIGAN.

BACK-SPACERS FOR TYPE-WRITERS.

1,163,134.

Specification of Letters Patent.

Patented Dec. 7, 1915.

Application filed December 14, 1907, Serial No. 403,409. Renewed January 18, 1912. Serial No. 671,887.

To all whom it may concern:

Be it known that I, WILLIAM R. FOX, a citizen of the United States, residing at Grand Rapids, in the county of Kent, State of Michigan, have invented certain new and useful Improvements in Back-Spacers for Type-Writers, of which the following is a specification.

This invention relates to improvements in back-spacers for typewriting machines.

The objects of the invention are to provide a simple and very effective means of back-spacing, which can be readily applied to or removed from a typewriting machine.

A further object is to provide an effective stop means for limiting the back throw of the back-spacer.

Objects pertaining to details of construction will definitely appear from the detailed description to follow.

I accomplish the objects of my invention by the devices and means described and illustrated in the following specification.

The invention is clearly defined and pointed out in the claims.

The features of my invention are fully illustrated in the accompanying drawing, forming a part of this specification, in which:

Figure 1 is a rear view of the top portion of a type-writer and its escapement mechanism with my improved back-spacer in place; Fig. 2 is a plan view of the structure appearing in Fig. 1, the top-plate of the typewriter and the connection to the back-spacer being shown in broken sections; Fig. 3 is a sectional view taken on line 3—3 of Fig. 1, showing the details of construction at this point; Fig. 4 is a similar detail sectional view taken on line 4—4 of Fig. 1; and Fig. 5 is a similar detail sectional view, taken on line 5—5 of Fig. 1, showing the relation of the escapement dogs to the teeth of the escapement-wheel.

In the drawing, the sectional views are taken looking in the direction of the little arrows at the ends of the section lines, and similar letters of reference refer to similar parts throughout the several views.

Referring to the numbered parts of the drawing, portions of the top-plate 1 of a typewriter are illustrated; a portion of the rack 2, which is connected to the carriage, is also illustrated; and the escapement-wheel 3, with its pinion 4 for engaging the rack, are also shown in their proper position, as

they are carried by suitable brackets or supports on the top-plate of the typewriting machine.

The dog-block 5 is supported on the rock-shaft 6 which is pivoted above the top of the machine. The dogs are made adjustable by suitable mechanism actuated from the lever 7, which mechanism, as it has nothing especially to do with this invention, will not be further described, it merely being illustrated to show a usual construction of such parts. A bracket 8 is secured to the top-plate 1 and extends upwardly and is curved over the top of the rock-shaft 6, and the upper part of the bracket is re-curved at 8' to serve as a guide. A pin-stop 8'' is inserted in this bracket. The back-spacer push-bar 9 fits into the guide 8' and is held normally retracted by the coiled spring 9' which connects the rear part of the same to any convenient portion of the machine. This push-bar is connected to the bell-crank lever 10 which is pivoted at 11 on the top-plate of the machine. A push-rod 12 extends through the front-plate of the machine through a suitable guiding hole therein, and is provided with a push-button 13 for controlling the same. The front end of the push-bar 9 is provided with a notched catch 9'' on its upper surface and is beveled on the underside. The catch is positioned to engage one of the teeth of the escapement-wheel. The beveled underside contacts with the stop-pin 8'' which locks the plunger when it is advanced to the predetermined point necessary to back-space the carriage one space or any predetermined number of spaces. The beveled end of the push-bar causes it to rise toward the center of the escapement wheel, so that when the limit of the stroke is reached, it tends to clamp the wheel by pressing the projecting end of the said push-bar against the periphery thereof and thus effectively stops the same. Of course the escapement wheel is returned one notch, the escapement dogs yield, as is usual in such constructions, and the carriage is effectively back-set.

The virtues of this structure are its extreme simplicity and effectiveness and its entire independence from other parts of the machine than that which are concerned in the operation of the device.

Having thus described my invention, what I claim as new and desire to secure by Letters Patent is:

1. In a typewriting machine, the combination with a wheel-escapement of a bracket on the top-plate having a suitable guide thereon and a stop-pin; a push-bar arranged in the guide of said bracket, tangentially to said wheel, and having a notched catch for 25 engaging one of the teeth of the escapement-wheel; and beveled on its underside to contact with the said stop; a bell-crank 30 lever fulcrumed on the top-plate of the typewriter and connected to the said push-bar; a spiral spring connected to hold the said push-bar normally retracted; and a push-rod connected to said bell-crank lever and 35 extending through the front-plate of the machine and provided with suitable push-button for controlling the said back-spacer, all co-acting substantially as described and for the purpose specified.
2. In a typewriting machine, the combination with a wheel-escapement of a bracket

on the top-plate having a suitable guide thereon and a stop-pin; a push-bar arranged in the guide of said bracket, tangentially to said wheel, and having a notched catch for 25 engaging one of the teeth of the escapement-wheel; and beveled on its underside to contact with the said stop; a bell-crank lever fulcrumed on the top-plate of the typewriter and connected to the said push-bar; 30 a spiral spring connected to hold the said push-bar normally retracted; and connections to the front of the machine for actuating the said push-bar, for the purpose specified.

In witness whereof, I have hereunto set my hand and seal in the presence of two witnesses.

WILLIAM R. FOX. [L.S.]
